UNITED STATES PATENT OFFICE.

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC TRAIN-SPEED-CONTROL APPARATUS.

Application filed April 23, 1919. Serial No. 292,209.

To all whom it may concern:

Be it known that I, THOMAS H. THOMAS, a citizen of the United States, residing at Edgewood, in the county of Allegheny and 5 State of Pennsylvania, have invented new and useful Improvements in Automatic Train-Speed-Control Apparatus, of which the following is a specification.

This invention relates to an automatic 10 train speed control apparatus, and is in the nature of an improvement of the construction covered by the U. S. Patent No. 1,316,205 of Walter V. Turner, dated September 16, 1919.

15 While with an apparatus of the above character, the speed of the train is controlled automatically, it is considered desirable for the engineer to be on the alert, and to ensure that he notes the signal indication, one 20 object of my invention is to provide means for imposing a penalty, in the way of reducing the speed below that required for the particular signal indication, if the engineer, on passing the signal, fails to perform a required act.

In applying the brakes with the usual 25 fluid pressure brake, if the brake pipe reduction be too light to effect an appreciable reduction in auxiliary reservoir pressure by 30 operation of the triple valve device in supplying fluid from the auxiliary reservoir to the brake cylinder, it may happen that when the brake pipe pressure is increased to release the brakes, the differential pressure 35 will not be sufficient to effect the release movement of the triple valve pistons.

Another object of my invention is to provide means for ensuring a predetermined reduction in brake pipe pressure under all 40 conditions, and sufficient to ensure the positive subsequent release of the brakes upon increasing the brake pipe pressure.

If the brakes are released while fluid is 45 still being discharged from the brake pipe by the operation of the equalizing discharge valve mechanism, the brake pipe pressure not having had time to equalize throughout the length of the brake pipe, shocks are liable to occur, due to the brakes 50 being held applied at the rear end while they are being released at the head end.

Another object of my invention is to overcome this difficulty by providing means for ensuring the substantial equalization of

brake pipe pressure throughout the train 55 before the brakes can be released.

Other objects and advantages will appear in the following more detailed description of the invention.

In the accompanying drawings, Fig. 1 is 60 a diagrammatic sectional view of an automatic train speed controlling apparatus embodying my invention and showing the parts in the positions assumed when the track circuits are imposing the low speed limit on 65 the apparatus and the speed of the train is less than the low speed limit; Fig. 2 an enlarged sectional view of the penalty valve portion of the speed controlling apparatus, showing the parts in the positions assumed 70 upon passing a caution signal indication, with the penalty push button held depressed by the engineer; Fig. 3 a view similar to Fig. 2, but showing the parts in the positions assumed if the engineer does not depress the penalty push button upon passing a caution signal indication; Fig. 4 an enlarged sectional view of the change speed valve device in low speed position; Fig. 5 75 a similar view of the change speed valve 80 device, showing the same in the medium speed position; Fig. 6 an enlarged sectional view of the application valve device in application position; and Fig. 7 a similar view of the application valve device, showing the 85 same in lap position.

As shown in Fig. 1 of the drawings, the preferred construction embodying my invention may comprise speed magnets A and B, adapted to be controlled by track circuits, a speed governor valve portion C, a change speed valve device D, a brake application valve device E, a penalty valve device F, a valve device G, a retarded application valve device H, equalizing discharge 95 valve mechanisms K and L, release timing discharge valve mechanism M, push button penalty valve N, and push button release valve O.

The change speed valve device D is for the 100 purpose of determining the speed limit at which the speed governor valve portion C will act and comprises a piston device having connected differential piston heads 1 and 2 for operating a slide valve 3. The slide 105 valve has three positions—a low speed position, a medium speed position, and an intermediate high speed position.

The brake application valve device E may comprise a piston device having connected differential piston heads 4 and 5 for operating a slide valve 6.

5 The speed governor valve portion C comprises a centrifugal device 7 of the ordinary type adapted to be rotated in accordance with the speed of the vehicle by a suitable operative connection to the axle of the vehicle through the pinion 8. The centrifugal device 7 operates a sliding stem 9 to which is attached a plate 10 having a series of adjusting screws 11, 12, 13, 14, and 15 for engaging and operating respectively a low speed delayed application valve 16, a low speed valve 17, a medium speed valve 18, a high speed valve 19, and a high speed delayed application valve 20.

10 The penalty valve device F may comprise a piston 21 and a slide valve 22 and the valve device G a piston 23 and slide valve 24.

15 The delayed application valve device H may comprise a valve piston 25 and a poppet valve 26 adapted to be operated by the piston 25.

20 The speed magnet A controls double beat valves 27 and 28; and the speed magnet B, the double beat valves 29 and 30.

25 The brakes may be manually controlled by the usual automatic brake valve 31 and independent brake valve 32; the automatic brake valve 31 comprising a rotary valve 33 contained in valve chamber 34 and adapted 30 to be operated by handle 35 and the usual equalizing discharge valve mechanism 36 for controlling and regulating the venting of fluid under pressure from the brake pipe 37, to effect an application of the brakes.

35 The independent brake valve 32 may comprise a rotary valve 38, contained in valve chamber 39, and adapted to be operated by handle 40.

40 The track circuits for controlling the magnets A and B and the means by which the magnets are energized or deenergized, form no part of my invention, but it may be stated that a system has been provided so that for a clear indication permitting high speed, the magnets A and B are both energized; for a caution indication permitting medium speed, the magnet A is deenergized and magnet B energized; while for a danger indication permitting only a low speed, both magnets are deenergized.

45 With the usual main reservoir 41 charged with fluid under pressure, fluid is supplied through pipe 42 and passage 43 to valve chamber 44 of valve device G and from valve chamber 44 through passage 45 to valve chamber 46 of valve device F.

50 From valve chamber 46 fluid equalizes through port 47 in piston 21 to piston chamber 48. Fluid also flows from passage 43 through passage 49 to valve chamber 50

of valve device E and from valve chamber 50 fluid flows through passage 51 to valve chamber 52 of valve device D. Fluid under pressure also equalizes from the valve chamber 50 through the restricted port 96 into 55 piston chamber 85.

60 The chamber above the equalizing discharge piston 53 and the equalizing reservoir No. 1 connected thereto, are charged from the brake pipe when the application slide valve 6 is in release position, through passage 54, past check valve 55, passage 56, and cavity 57 in slide valve 6 to passage 58.

65 The equalizing reservoir No. 2 and the chamber above equalizing discharge piston 59 are also charged through cavity 57 by way of passage 60.

70 Timing reservoir No. 1 is charged from valve chamber 46, with slide valve 22 in its inner position, through port 61 and passage 62. Timing reservoir No. 2 is charged from valve chamber 44 of valve device G when the slide valve 24 is in its inner position, through port 63 and passage 64.

75 The reduction reservoir No. 1 is connected to the atmosphere in the release position of application slide valve 6, through passage 65 and cavity 66 to exhaust port 67 and reduction reservoir No. 2 is connected to atmospheric exhaust port 68 through passage 69 and cavity 70 in slide valve 6.

80 In operation, if the signal indication is clear, the track circuits cause both the magnets A and B to be energized, so that the valves 27 and 29 are seated and the valves 28 and 30 opened.

85 The opening of valve 30 operates to supply fluid under pressure to piston chamber 72 of valve device G from valve chamber 50 through passages 71 and 73, so that piston 23 and slide valve 24 are shifted to their inner positions.

90 The opening of valve 28 effects the supply of fluid to piston chamber 74 of the speed limit selector valve device D from valve chamber 52 through passage 71, passage 75, cavity 76 in slide valve 22, and passage 77, and also to piston chamber 78 of piston 2 through the same cavity 76, passage 79, cavity 80 in slide valve 24, and passage 81.

95 As fluid under pressure is thus supplied to the outer faces of the pistons 1 and 2, one or the other of the spring stops 82 or 83 will move the valve device to its intermediate or high speed position, dependent upon the position the valve device happens to be in. In the high speed position of slide valve 3, the passages are blanked which control the train for low and medium speeds and the movement of the brake application valve device E is only effected by the high speed valve 19 which controls passage 84 leading to the piston chamber 85 of piston 4.

100 If the speed of the train should exceed 130

the high speed limit, which may be 60 miles per hour, for example, then the speed governor 7 operates the stem 9 so as to open the valve 19 and thereby vent fluid from piston 5 chamber 85. The piston 4 then shifts the slide valve 6 to its outer application position, in which the reduction reservoir No. 1, now at atmospheric pressure is connected to the charged equalizing reservoir No. 10 through passage 65, cavity 66 in slide valve 6, and passage 58.

The reduction reservoir No. 2, also at atmospheric pressure is connected to the charged equalizing reservoir No. 2 through 15 passage 69, cavity 70 in slide valve 6, and passage 60.

The pressures in the equalizing reservoirs No. 1 and No. 2 are thus vented into the corresponding reduction reservoirs No. 1 20 and No. 2 and this permits the higher brake pipe pressure acting on the opposite sides of the equalizing pistons 53 and 59 to lift the pistons and open the corresponding discharge valves 86 and 87. Fluid is therefore 25 upon vented from the brake pipe 37 to effect an application of the brakes throughout the train in the well known manner.

If the speed of the train is reduced to the predetermined speed limit, before the equalizing reservoir pressure has fully equalized into the reduction reservoir, it will still require a little time for the brake pipe pressure to equalize or stabilize throughout the train, especially if the train be a long one, 35 and in order to prevent shocks, it is desirable that no release of the brakes take place during this period. Accordingly, the possible release of the brakes is delayed for a time in the following manner.

40 The discharge from the equalizing discharge valves 86 and 87, instead of being vented to the atmosphere in the usual manner is vented to a release timing reservoir 88, since the opening of either discharge 45 valve 86 or 87 vents fluid to a common passage 137 and thence through cavity 138 in the slide valve 6, when said valve is in application or lap positions, to passage 139, which leads to the release timing reservoir 50 88 and the chamber above the piston 89 of the discharge valve device M.

The piston 89 operates a discharge valve 98 for venting fluid from beneath the small piston 5 of the application valve device E 55 through a passage 100 to an atmospheric exhaust port 102, so that the release movement of said application valve device is effected by the action of the discharge valve device M.

60 The release of the brakes is controlled by the engineer with certain limitations and for this purpose the push button release valve device O is provided.

When the application valve device E is 65 in application position, the push button

valve 90 controls an exhaust outlet 91, which is connected to piston chamber 85, through passage 92, cavity 93 in slide valve 6, passage 94, and pipe 95. A spring 96 normally holds the valve 90 open, so that in the 70 application position of the piston 4, the piston chamber 85 is maintained at atmospheric pressure, so as to prevent the release movement of the piston 4, until the engineer, desiring to release the brakes, presses the 75 push button valve 90 to its seat.

This cuts off the exhaust outlet 91 from the piston chamber 85, but no action will take place so long as the speed of the train exceeds the particular predetermined speed 80 limit selected, in the present instance, the high speed limit. Consequently, the high speed valve 19 continues to maintain the piston chamber 85 at atmospheric pressure until the speed has been reduced to the pre- 85 determined speed limit.

So long as the application valve device E remains in application position, the fluid in the equalizing reservoirs 1 and 2 will continue to equalize into the respective reduction reservoirs 1 and 2 until the pressures become fully equalized.

As soon as the speed of the train has been reduced to the predetermined speed limit, the high speed valve 19 is permitted to close 95 and then, the push button valve 90 being held closed, fluid pressure will equalize through port 96 in piston 4 to piston chamber 85, permitting the spring stop 97 to move the application piston 4 to lap position. 100

In lap position, the slide valve 6 cuts off communication from the piston chamber 85 to exhaust outlet 91, so that the engineer may now release the push button valve 90. 105

By the movement of slide valve 6 from application to lap position, communication from the reduction reservoir No. 1 through passage 65, cavity 66, and passage 58 to the equalizing reservoir No. 1 is cut off, but communication from the reduction reservoir No. 2 through passage 69, cavity 70 in slide valve 6, and passage 60, is maintained, as well as communication from the discharge valves 86 and 87 through passage 137, cavity 138, 110 and passage 139 to the timing reservoir 88, 115 and as will be evident from Fig. 7.

The reduction reservoir No. 1 being cut off from the equalizing reservoir No. 1, further reduction in pressure in the equalizing 120 reservoir No. 1 is prevented and when the brake pipe pressure has been reduced to a degree slightly less than the pressure in said equalizing reservoir, the piston 53 is operated to close the discharge valve 86. 125

The reduction reservoir No. 2, however, is still in communication with the equalizing reservoir No. 2 and the reduction in pressure in equalizing reservoir No. 2 continues until equalization takes place, and then when the 130

brake pipe pressure reduces to a point slightly less than the pressure in said reservoir, the piston 59 operates to close valve 87.

In the application as well as the lap position of the slide valve 6, the common discharge passage 137 from the discharge valves 86 and 87 is connected through cavity 138 in slide valve 6 with passage 139, leading to the timing reservoir 88.

10 So long as the discharge valves 86 and 87 are venting fluid to the timing reservoir 88, the piston 89 operates to hold the valve 98 seated, but when the discharge valves close, the pressure in the timing reservoir 88 15 gradually escapes through an atmospheric vent port 99. The valve 98 controls a passage 100 leading to the piston chamber of piston 5 of the application valve device E and when the valve device is not in normal 20 release position, a groove 101 permits the equalization of fluid pressure from valve chamber 50 to said piston chamber.

This fluid pressure acts on the exposed 25 area of the discharge valve 98, and when the pressure in the timing reservoir has been reduced to a low point by venting through the port 99, the pressure on the valve 98 will lift the valve and permit the venting of fluid from the small piston 5, through passage 100 to exhaust port 102.

It will be noted that two equalizing discharge valve mechanisms are employed and that the equalizing reservoir of the discharge valve mechanism K is cut off from the corresponding reduction reservoir when the application slide valve 6 moves to lap position, while the equalizing reservoir of the discharge valve mechanism L remains in communication with its corresponding reduction reservoir. The purpose of this is to ensure a sufficient reduction in brake pipe 30 pressure, say seven pounds, for example, so that there will follow a reduction in auxiliary reservoir pressure at each triple valve device throughout the train, sufficient to ensure 35 that a subsequent increase in brake pipe pressure will be effective to release the brakes. If the reduction in brake pipe pressure be too light, then there is danger that the brake pipe pressure cannot be increased 40 sufficiently to cause such a differential pressure as to ensure the release movement of the triple valves. The volume of the reduction reservoir No. 2 is, of course, such that 45 the desired reduction in brake pipe pressure is secured.

The reduction of pressure thus produced 50 on piston 5 is sufficient to destroy the equilibrium of fluid pressures acting on the application piston device, so that the application valve device will now be shifted to release position, in which the rotary valve chamber 34 of the engineer's brake valve 31 is again connected to the main reservoir by 55 flow from the valve chamber 50, through

port 103, passage 104, pipe 105, and passage 106.

Fluid is then supplied through the brake valve in the usual manner to the brake pipe to effect the release of the brakes throughout 70 the train.

When the application valve device is shifted to lap position, while the reduction reservoir No. 1 is cut off from the equalizing reservoir No. 1, as before described, unless full 75 equalization of pressures has taken place, the brake pipe pressure will be somewhat higher than the pressure in the equalizing reservoir No. 1 and in order to effect the quick equalization of pressures on the discharge piston 80 53, the equalizing reservoir No. 1 is connected in lap position of the application slide valve 6 with the brake pipe 37, through passage 58, cavity 57 in slide valve 6, passage 56, past check valve 55, to passage 54.

If the brakes are applied by manipulation of the engineer's brake valve, the brake pipe pressure is reduced in the usual manner and as brake pipe pressure is present below the equalizing discharge valve pistons 90 53 and 59, it will be seen that a higher pressure is then present in the equalizing reservoirs 1 and 2. This higher pressure may leak past the equalizing pistons 53 and 59 95 after the brakes have been applied and then tend to release the brakes.

In order to avoid this possibility, the pistons 53 and 59 are provided with collapsible 100 valve portions, so that when the equalizing reservoir pressure exceeds the brake pipe pressure, the pistons 53 and 59 will be moved downwardly compressing springs 107 and 108 so as to open the respective equalizing grooves 109 and 110 and thus permit the 105 quick equalization of any excess pressure in the equalizing reservoirs into the brake pipe.

If the brakes are released by manipulation of the engineer's brake valve, the pressure on the brake pipe side of the pistons 53 and 59 is increased and this pressure will lift the 110 pistons and open the corresponding discharge valves, if the equalizing reservoir pressure be less than the brake pipe pressure.

In order to prevent the venting of fluid from the brake pipe by the opening of the discharge valves 86 and 87, the discharge passage 137 is controlled by the application slide valve 6, so that in the normal release position of the slide valve, the discharge passage is closed, thus preventing the venting 115 of fluid from the brake pipe, if the discharge valves should open.

In the release position of the application slide valve E, the reduction reservoirs 1 and 2 are again connected to the atmosphere 120 while the equalizing reservoirs will be connected to the brake pipe, so as to effect the recharging of same with fluid under pressure in readiness for the next operation.

If the signal indication is for caution, the 125

apparatus will be adjusted so as to limit the speed to a medium speed limit, say 35 miles per hour, for example.

In this case, the track circuits cause the speed magnet A to be deenergized and the speed magnet B to be energized.

The magnet B being energized, the valve 29 will be closed, and the valve 30 opened to supply fluid from the main reservoir to the piston chamber 72 of valve device G, as in the case of high speed control hereinbefore described. The piston 23 therefore shifts the slide valve 24 to its inner position.

The effect of the deenergization of magnet A depends on the position of the valve device F and involves the operation of that feature of my invention which I have termed the penalty or suppressed application feature.

According to this feature, the engineer must perform an act when he sees that the signal indication is for caution in order to retain the medium speed limit permitted under a caution indication. If he does not, whether because he is incapacitated or is inattentive to his duties, then the speed limit will be reduced to the low speed limit.

For accomplishing the above, I provide a penalty valve device N, having a push button valve 111, which when depressed will connect the piston chamber 48 of valve device F with the atmosphere, through passage 112, cavity 113 in application slide valve 6, passage 114, and pipe 115.

The venting of fluid from piston chamber 48 causes piston 21 to shift the slide valve 22 to its outer position, in which the piston chamber 74 of the speed limit selector valve device D is connected to the valve chamber 40 of valve 26, through passage 77, cavity 116 in slide valve 22, passage 117, cavity 118 in slide valve 24, and passage 119.

The chamber above the valve piston 25 of the valve device H is connected to the high speed delayed application valve 20 through passage 120, cavity 121 in slide valve 24, passage 122, cavity 123 in slide valve 22, and passage 124. With the slide valve 22 in its outer position, as shown in Fig. 2 of the drawings, the retarded application timing reservoir No. 1 is also connected to the chamber above the valve piston 25 through passage 62, cavity 123 in slide valve 22, passage 122, cavity 121 in slide valve 24, and passage 120 and the speed valve 20 is also connected to the retarded application timing reservoir No. 1 through passage 62, cavity 123 in slide valve 22, and passage 124.

The movement of slide valve 22 to its outer position also connects the magnet valve A to the piston chamber 48, through passage 75, cavity 76 in slide valve 22, and passage 112, so that, the magnet A being deenergized, the piston chamber 48 will be maintained at atmospheric pressure, thus permit-

ting the engineer to release the penalty valve 111.

The passage 81, leading to piston chamber 78 of valve device D is connected through cavity 80 in slide valve 24 with passage 79, but since the passage 79 is now blanked by slide valve 22, fluid pressure will be bottled up in piston chamber 78.

The valve 20, being now connected to the charged timing reservoir No. 1, will vent fluid therefrom at a certain rate. This valve is so designed as to vary the vent opening in such a way that fluid is vented from the timing reservoir No. 1 at a rate proportional to the speed of the train and when the pressure in the timing reservoir has been reduced to a predetermined degree, the valve device H is operated to vent fluid from the small piston 1 of the valve device D, so as to cause the same to be shifted to its medium speed position.

More in detail, when the pressure in the timing reservoir No. 1 is reduced to a predetermined degree, the feed valve pressure acting on the under side of the valve piston 25, through pipe 127 and passage 128, lifts the valve piston so as to open the valve 26. The piston chamber 74 of the speed valve device D is then connected to the speed valve 20 and the timing reservoir No. 1, so that fluid is vented from the face of piston 1, permitting the pressure in piston chamber 78 to force the valve device to its upper or medium speed position.

In this position, passage 84, leading to piston chamber 85 of the application valve device E is connected, through cavity 125 in slide valve 3 with passage 126, leading to the medium speed controlling valve 18. If the speed of the train exceeds the medium speed limit, say for example 35 miles per hour, the valve 18 will be in open position, and fluid will be vented from the piston chamber 85, to effect the movement of the application valve device E to application position, in which the brakes are applied to reduce the speed of the train in the manner hereinbefore described. If the speed of the train does not exceed the medium speed limit, then the application valve device will not be operated, and no action takes place.

As a train will obviously move over a greater distance, before the speed is reduced to the desired speed, the greater the speed of the train, by employing the mechanism above described for delaying the application of the brakes according to the speed of the train, the speed of the train can be maintained until the point is reached at which, by applying the brakes, the speed will be reduced to the desired speed limit by the time the train reaches the place where the reduced speed becomes necessary.

The brakes may be released by the engineer under the same limitations as de-

scribed in connection with running at the high speed limit.

If the engineer does not depress the push button valve 111 in passing a caution indication, then the valve device F will remain in its inner position, in which the piston chamber 78 of the valve device D is connected to the exhaust through passage 81, cavity 80 in slide valve 24, passage 79, cavity 76 in slide valve 22, passage 75, and past the open valve 27 of the speed magnet A to the atmosphere.

The piston chamber 74 is also connected to the speed magnet valve 27 through passage 77 and cavity 76, but since the piston 2 is of greater area than the piston 1, the unbalanced pressure between the pistons will shift the valve device to its lower or low speed position, in which communication is established from the piston chamber 85 of the application valve device E to the low speed valve 17 through passage 84, cavity 129 in slide valve 3 and passage 130.

It will now be evident that if the speed of the train exceeds the low speed limit, say 15 miles per hour, for example, the valve 17 will be opened, and fluid vented from piston chamber 85 to operate the application valve device so as to effect an application of the brakes as hereinbefore described.

Thus if the engineer fails to depress the push button valve 111 in passing a caution signal, the speed of the train will be reduced to the low speed limit, instead of the medium speed limit, as would have been the case had he depressed the valve.

If the engineer should wait until after he passes the caution indication and then press the penalty valve 111, no action will take place, because the application valve will now be in application position, in which the penalty valve 111 is cut off from the valve device F.

If a caution indication is passed and the speed of the train is reduced to the medium speed limit, as hereinbefore described, and the next signal indication is at danger, then a low speed indication will affect the magnets A and B at a certain distance in advance of the danger signal. For low speed, both magnets are deenergized and since the valve 29 of the magnet B is open, fluid is vented from the piston chamber 72 of the valve device G, so that the same will be shifted to its outer position, in which the low speed delayed application valve 16 and the delayed application timing reservoir No. 2 are connected to the chamber above the valve piston 25, by means of cavity 131, which connects passage 132, leading to the valve 16, with passages 120 and 64. When the pressure in the delayed application timing reservoir No. 2 has been reduced to a predetermined degree by flow past the valve 16, dependent upon the speed of the train and the

consequent outlet vent area at the valve 16, similar to the action described in connection with the valve 20, then the feed valve pressure acting on valve piston 25 will lift same so as to open the valve 26 and thus connect the valve 16 with piston chamber 78 of the speed valve device D through passage 81, cavity 133, in slide valve 24, passage 119, and past valve 26 to passage 120, which is now connected to the valve 16 as before described.

The speed valve device will therefore be shifted to the low speed position by the venting of fluid pressure from the piston chamber 78, and the piston chamber 85 of the application valve device E will be connected to the low speed valve 17, so that if the speed of the train exceeds the low speed limit, and the valve 17 is thus open, the application valve device E will be operated to effect an application of the brakes.

While the operation above described refers to the action which takes place after a caution indication is passed, it will be understood that the same action occurs in case the signal indication is changed from clear or high speed directly to danger indication or low speed.

When the application valve device E is shifted to application position, the flow of fluid from the main reservoir to the rotary valve chamber 34 is cut off, and there is then some possibility that the brake pipe pressure acting below the rotary valve 33 may lift same from its seat. In order to prevent this, said valve chamber is connected to the brake pipe in the application position as well as the lap position of the application valve device by way of passage 54, past check valve 134, through passage 135, cavity 136 in slide valve 6, to passage 104, which leads to the pipe 105.

It will be noted in the foregoing description of operation, that when the apparatus is set for low speed by the action of the track signal circuits, the delayed application mechanism is brought into action, while if a caution indication is passed without the engineer operating the penalty push button, the low speed limit is cut in but operates immediately, since the delayed application mechanism is then cut out.

When the valve device F is shifted to its outer position, the piston chamber 48 is connected to the speed magnet A, so that if the signal indication should change from caution to clear, the magnet A being energized, will operate to open the valve 28, so as to supply fluid to the piston chamber 48. The piston 21 will then shift the slide valve 22 to its inner position, in which communication is established for varying the fluid pressure on the train speed limit selector valve device D, so that the same is shifted to its high speed position. It will now be

evident that if the release valve O be operated to release the brakes, the brakes will be released without waiting for the speed to be reduced to the medium speed limit.

5 If it is desired to provide an automatic release of the brakes without action on the part of the engineer, this can evidently be secured by merely plugging up passage 94, leading to the manually operated release 10 valve O.

Having now described my invention, what I claim as new, and desire to secure by Letters Patent, is:—

1. In a train speed control apparatus, the 15 combination with a brake valve device for controlling the brakes and mechanism controlled from the trackway for imposing a predetermined train speed limit, of means manually operable by the engineer independently of said brake valve device for permitting a higher train speed limit.

2. In a train speed control apparatus, the combination with a brake valve device for controlling the brakes and mechanism controlled from the trackway for imposing a predetermined train speed limit, of means 20 separate from said brake valve device and operable by the engineer to prevent the imposition of said predetermined train speed limit.

25 3. In a train speed control apparatus, the combination with a brake valve device for controlling the brakes and mechanism operable to impose a higher or a lower predetermined train speed limit on the train, of means controlled by the engineer separately from the brake valve device for setting said mechanism to impose the higher speed limit and means controlled from the trackway for 30 setting said mechanism to impose the lower speed limit, if the engineer fails to act.

35 4. In a train speed control apparatus, the combination with mechanism operable to impose a higher or a lower train speed limit on the train, of fluid pressure controlled means operable by the engineer for causing said mechanism to impose the higher speed limit and means controlled from the trackway for causing said mechanism to impose the lower speed limit, if the engineer fails to act.

40 5. In a train speed control apparatus, the combination with mechanism operable to impose a higher or a lower train speed limit on the train, of a brake valve device for controlling the brakes, fluid pressure controlled means operable independently of said brake valve device for setting said mechanism to impose the higher speed limit, and means 45 controlled from the trackway for setting said mechanism to impose the lower speed limit, if the engineer fails to operate said fluid pressure controlled means.

50 6. In a train speed control apparatus, the combination with a train speed limit selector

valve device having positions for imposing different train speed limits, of means subject to track signal control for varying the fluid pressure on said selector valve device to determine the position thereof and a penalty valve device normally establishing communication through which said means controls the fluid pressure on the selector valve device and adapted to be operated by the engineer for cutting off said communication and for independently varying the fluid pressure on said selector valve device.

7. In a train speed control apparatus, the combination with a train speed limit selector valve device operated by fluid pressure for imposing different train speed limits, of a valve device controlled by the track signal system for controlling communication through which the fluid pressure is varied on said selector valve device and a valve device controlled by the engineer for also controlling communication through which the fluid pressure is varied on said selector valve device.

8. In a train speed control apparatus, the combination with a train speed limit selector valve device operated by fluid pressure for imposing different train speed limits, of a valve device normally establishing communication through which the fluid pressure is varied on said selector valve device to move the same to one speed limit position, a valve device for applying the brakes at a speed limit corresponding with the position of the selector valve device, and a valve device controlled by the engineer for controlling communication through which the fluid pressure is varied on said selector valve device to move same to another speed limit position, said communication being also controlled by said application valve device.

9. In a train speed control apparatus, the combination with a valve device operated upon a reduction in fluid pressure for applying the brakes and means controlled according to the speed of the train for reducing the pressure on said application valve device, of a manually operated release valve for also controlling the fluid pressure on said valve device.

10. In a train speed control apparatus, the combination with a valve device operated upon a reduction in fluid pressure for applying the brakes and means controlled according to the speed of the train for reducing the pressure on said application valve device, of a manually operated release valve for also controlling the fluid pressure on said valve device through a communication controlled by said valve device.

11. In a train speed control apparatus, the combination with a slide valve, a piston operated upon a reduction in fluid pressure for actuating said slide valve to effect an application of the brakes, and means controlled

- according to the speed of the train for reducing the pressure on said piston, of a manually operated release valve for also venting fluid from said piston in application position and adapted to be operated for cutting off the venting of fluid from said piston and thereby permitting the equalization of fluid pressures on said piston.
12. In a train speed control apparatus, the combination with an application valve device having a piston subject on one side to fluid pressure and having means tending to equalize the fluid pressures on opposite sides of the piston and speed controlled means for reducing the fluid pressure on said piston, of a release valve operated by the engineer for closing a vent port to said piston and means for moving said piston to lap position upon equalization of fluid pressures thereon.
13. In a train speed control apparatus, the combination with a brake application valve device and speed controlled means for effecting the movement thereof to application position, of means controlled by the engineer for effecting the movement of said application valve device to lap position, and means operated upon a predetermined brake application for effecting the further movement of said valve device to release position.
14. In a train speed control apparatus, the combination with a brake pipe, a valve device for establishing communication for effecting a reduction in brake pipe pressure to apply the brakes, and speed controlled means for effecting the movement of said valve device to application position, of means controlled by the engineer for effecting the movement of said application valve device to lap position and means operated upon a predetermined reduction in brake pipe pressure for effecting the movement of the application valve device to release position.
15. In a train speed control apparatus, the combination with a brake pipe, of an equalizing reservoir, a discharge valve device subject to the opposing pressures of the equalizing reservoir and the brake pipe for venting fluid from the brake pipe upon a reduction in pressure in the equalizing reservoir, and a timing reservoir into which fluid is vented from the brake pipe by operation of said discharge valve mechanism.
16. In a train speed control apparatus, the combination with a brake pipe, of an equalizing reservoir, a discharge valve device subject to the opposing pressures of the equalizing reservoir and the brake pipe for venting fluid from the brake pipe upon a reduction in pressure in the equalizing reservoir, an application valve device for controlling communication through which fluid is vented from the equalizing reservoir, a timing reservoir into which fluid is vented from the brake pipe, and means controlled by the pressure in the timing reservoir for control-

ling the movement of said application valve device.

17. In a train speed control apparatus, the combination with a brake pipe, of an equalizing reservoir, a discharge valve device subject to the opposing pressures of the equalizing reservoir and the brake pipe for venting fluid from the brake pipe upon a reduction in pressure in the equalizing reservoir, an application valve device for controlling communication through which fluid is vented from the equalizing reservoir, a timing reservoir into which fluid is vented from the brake pipe and communicating with a restricted vent port, and means operated upon a reduction in pressure in the timing reservoir for varying the pressure on said application valve device to effect the movement thereof to release position.

18. In a train speed control apparatus, the combination with a brake pipe and a valve mechanism for venting fluid from the brake pipe, of an application valve device for controlling the operation of said valve mechanism and also communication through which said valve mechanism vents fluid from the brake pipe.

19. In a train speed control apparatus, the combination with a brake pipe and an application valve device operated when the speed of the train exceeds a predetermined speed limit, of an equalizing reservoir and an equalizing discharge valve mechanism subject to the opposing pressures of the equalizing reservoir and the brake pipe and controlled by said application valve device for venting fluid from the brake pipe, and having the communication through which fluid is vented from the brake pipe controlled by said application valve device.

20. In a train speed control apparatus, the combination with a brake pipe and an application valve device operated when the speed of the train exceeds a predetermined speed limit, of a valve mechanism controlled by said application valve device for venting fluid from the brake pipe and an additional valve mechanism controlled by said application valve device for also venting fluid from the brake pipe.

21. In a train speed control apparatus, the combination with a brake pipe and an application valve device operated when the speed of the train exceeds a predetermined speed limit, of an equalizing reservoir, an equalizing discharge valve mechanism subject to the opposing pressures of the equalizing reservoir and the brake pipe and controlled by the application valve device for venting fluid from the brake pipe, an additional equalizing reservoir, and an additional equalizing discharge valve mechanism subject to the opposing pressures of the additional equalizing reservoir and the brake pipe and controlled by said application valve

device for also venting fluid from the brake pipe.

22. In a train speed control apparatus, the combination with a brake pipe and an application valve device operated when the speed of the train exceeds a predetermined speed limit, of an equalizing discharge valve mechanism operated upon movement of the application valve device to application position for venting fluid from the brake pipe and adapted to be cut out of action upon movement of the application valve device to lap position and an additional equalizing discharge valve mechanism operated upon movement of the application valve device to application position for venting fluid from the brake pipe and adapted to remain in action upon movement of the application valve device to lap position.

23. In a train speed control apparatus, the combination with a brake pipe and an application valve device operated when the speed of the train exceeds a predetermined speed limit, of an equalizing discharge valve mechanism controlled by said application valve device for effecting a limited predetermined reduction in brake pipe pressure and another equalizing discharge valve mechanism controlled by said application valve device for effecting a greater reduction in brake pipe pressure.

24. In a train speed control apparatus, the combination with a brake pipe and an application valve device operated when the speed of the train exceeds a predetermined speed limit, of an equalizing discharge valve mechanism open in both the application and lap positions of the application valve device for effecting a limited predetermined reduction in brake pipe pressure and another equalizing discharge valve mechanism open only in the application position of said application valve device for effecting a greater reduction in brake pipe pressure.

25. In a train speed control apparatus, the combination with a train speed limit selector valve device, of a penalty valve device for controlling said selector valve device, a manually operated valve for controlling said penalty valve device, and an additional valve device for also controlling said selector valve device.

26. In a train speed control apparatus, the combination with an application valve device for effecting an application of the brakes if the speed of the train exceeds a predetermined speed limit, of means operating to delay the application of the brakes according to the speed of the train and additional means operating to delay the application of the brakes according to the speed of the train.

27. In a train speed control apparatus, the combination with a train speed limit selector valve device adapted to impose different

speed limits, of means operating to delay the operation of said valve device according to the speed of the train.

28. In a train speed control apparatus, the combination with a train speed limit selector valve device adapted to impose different speed limits, of valve means operating to delay the operation of said valve device when the train enters a medium speed zone, according to the speed of the train, and another valve means operating to delay the operation of said valve device when the train enters a low speed zone, according to the speed of the train.

29. In a train speed control apparatus, the combination with a brake pipe and an application valve device operating when the speed of the train exceeds a predetermined speed limit, of an equalizing reservoir and an equalizing discharge valve mechanism subject to the opposing pressures of the equalizing reservoir and the brake pipe for venting fluid from the brake pipe, the application valve device being adapted in application position to establish communication for venting fluid from the equalizing reservoir and in lap position for supplying fluid from the brake pipe to the equalizing reservoir.

30. In a train speed control apparatus, the combination with a main reservoir, a brake pipe, and a brake valve device having a valve chamber containing the usual rotary valve, of an application valve device for connecting said chamber to the main reservoir in release position and to the brake pipe in application position.

31. In a train speed control apparatus, the combination with a train speed limit selector valve device, of a valve device for controlling communication through which the selector valve device is shifted to the medium speed position upon passing a caution indication and adapted to be operated by a change in the indication from caution to clear for establishing communication through which the selector valve device is shifted to the high speed position.

32. In a train speed control apparatus, the combination with a change speed valve device operated by fluid pressure and having a medium and a high speed position, of a valve device for establishing communication through which fluid pressure is varied on said change speed valve device to shift same to the medium speed position upon passing a caution indication, and operated by a change in the indication from caution to clear for establishing communication through which fluid pressure is varied on said change speed valve device to shift same to the high speed position.

33. In a train speed control apparatus, the combination with a change speed valve device operated by fluid pressure, of a fluid

- pressure operated valve device controlling communication for varying the fluid pressure on said change speed valve device, a track circuit controlled magnet valve for varying the fluid pressure on the first mentioned valve device, a second fluid pressure operated valve device for controlling communication for varying the fluid pressure on the change speed valve device and a second track circuit controlled magnet valve for varying the fluid pressure on said second valve device.
34. In a train speed control apparatus, the combination with a change speed valve device operated by fluid pressure, of a fluid pressure operated valve device controlling communication for varying the fluid pressure on said change speed valve device, a track circuit controlled magnet valve for varying the fluid pressure on the first mentioned valve device, a second fluid pressure operated valve device for controlling communication for varying the fluid pressure on the change speed valve device, a second track circuit controlled magnet valve for varying the fluid pressure on said second valve device.
35. In a train speed controlled apparatus, the combination with a train speed limit selector valve device and track controlled means for effecting the movement thereof, of means for delaying the operation of said selector valve device according to the speed of the train.
36. In a train speed controlled apparatus, the combination with a train speed limit selector valve device and track controlled means for effecting the movement thereof, of means controlled by the speed of the train and interposed between the selector valve device and said track controlled means for delaying the operation of said selector valve device for a time interval which is substantially inversely proportional to the speed of the vehicle.
37. Railway traffic controlling apparatus comprising apparatus on a vehicle controlled from the trackway for giving proceed, caution and stop indications, means controlled by said apparatus for permitting the train to travel at high speed when the apparatus indicates proceed and for imposing a low speed limit when the apparatus indicates stop, means controlled by said apparatus upon changing from proceed to caution indication for applying the brakes, a brake valve device for controlling the brakes, and manually controllable means separate from said brake valve device for suppressing such brake application and imposing a medium speed limit when said apparatus changes from proceed to caution indication.
38. Railway traffic controlling apparatus comprising vehicle-carried means controlled from the trackway for causing certain speed restrictions upon a change from a more favorable to a less favorable traffic condition, a brake valve device for controlling the brakes, and manually operable apparatus on the vehicle, operable independently of said brake valve device, for suppressing said speed restrictions and imposing less severe speed restrictions if said apparatus is set into operation before the change of traffic condition occurs.
39. Railway traffic controlling apparatus comprising vehicle-carried means controlled from the trackway for causing certain speed restrictions upon a change from proceed to caution traffic conditions, and manually operable fluid pressure controlled apparatus on the vehicle for suppressing said speed restrictions and imposing less severe speed restrictions if said apparatus is set into operation before the change to caution traffic condition occurs.
40. In a train speed control apparatus, the combination with a reservoir, of means controlled according to the speed of the train for venting fluid under pressure from said reservoir and means operated upon a predetermined reduction in pressure in said reservoir for determining the speed limit of the train.
41. In a train speed control apparatus, the combination with a reservoir, of means for venting fluid under pressure from the reservoir at a rate proportional to the speed of the train and means operated upon a predetermined reduction in pressure in said reservoir for determining the speed limit of the train.
42. In a train speed control apparatus, the combination with a reservoir, of a device operated upon a predetermined reduction in fluid pressure in said reservoir for determining the maximum speed limit of the train and means for reducing the fluid pressure in said reservoir at a rate proportional to the speed of the train.
43. In a train speed control apparatus, the combination with two reservoirs normally charged with fluid under pressure, of a device movable upon a predetermined reduction in pressure in one reservoir to impose one train speed limit and movable upon a predetermined reduction in pressure in the other reservoir to impose another train speed limit and means for reducing the pressures in said reservoirs according to the speed of the train.
44. In a train speed control apparatus, the combination with speed controlling means operative upon a change in the signal indication for imposing a lower speed limit, of means operative to delay the operation of said speed controlling means for a time interval which varies inversely as the speed of the train.
45. In a train speed control apparatus, the combination with a speed controlling means

having different positions for imposing different speed limits on the train and operative upon a change in the signal indication for imposing a lower speed limit, of means operative to delay the movement of said speed controlling means from a higher to a lower speed limit position for a time interval which varies inversely as the speed of the train.

10 46. In a train speed control apparatus, the

combination with a train speed limit selector valve device movable to different positions for imposing different speed limits on the train and track controlled means for effecting the movement thereof, of means for delaying the movement of said selector valve device according to the speed of the train.

In testimony whereof I have hereunto set my hand.

THOMAS H. THOMAS.
